UNITED STATES PATENT OFFICE.

GEORGE W. NELSON, OF CLEVELAND, OHIO, ASSIGNOR TO THE STANDARD SEWING MACHINE COMPANY, OF CLEVELAND, OHIO, A CORPORATION OF OHIO.

THREAD-CONTROLLING MECHANISM FOR SEWING-MACHINES.

1,240,868.

Specification of Letters Patent. Patented Sept. 25, 1917.

Application filed November 12, 1913. Serial No. 800,495.

To all whom it may concern:

Be it known that I, GEORGE W. NELSON, a citizen of the United States, and resident of Cleveland, in the county of Cuyahoga and State of Ohio, have invented certain new and useful Improvements in Thread-Controlling Mechanism for Sewing-Machines, of which the following is a specification.

10 This invention relates to sewing-machines, and particularly to button-hole sewing machines, and the main object of the invention is to provide an improved pull-off mechanism of the general type disclosed in Patent 15 No. 805,870, granted November 28, 1905.

The invention constituting the subject-matter of the present application is distinguished from that of the aforesaid patent in various respects. One of the principal 20 features of difference is that the pull-off proper in the present invention has a variable movement in the general direction of pull-off instead of the fixed range of movement of the pull-off device of said patent.

25 In addition to this the pull-off of the present case is one that preferably has a variable movement in a single path, to wit, the path of pull-off, the extent of its movement in this path depending upon the amount of 30 thread it is desired to draw from the source of supply. This variable movement is best obtained by the conjoint action of controlling means for determining the range of movement of the pull-off device and of operating means for moving said device in its 35 pull-off path a distance determined by the action of such controlling means. This controlling means is also governed in a sewing machine of the button-hole type, in which

40 there is a shifting movement for locating the work properly with respect to two different sets of stitches to be made, by the action of the work-holder-shifting mechanism in a manner similar to that of the 45 aforesaid patent.

Another important feature of the present invention is the provision of a bobbin-holder adapted to be turned to permit an additional length of thread to be drawn from the bobbin carried by it, and suitable means cooperating with said bobbin-holder for positively turning the same to assure the delivery of such additional length of bobbin-thread.

50 Other features of the invention not here-

inbefore referred to will be hereinafter described and claimed and are illustrated in the accompanying drawings, in which—

Figure 1 is an under-side view of a button-hole sewing machine embodying pull-off mechanism constructed in accordance with my present invention; 60

Fig. 2 is an enlarged, vertical, transverse section of the same, the section being taken in line 2—2, Fig. 1, looking in the direction 65 of the arrow.

Fig. 3 is an enlarged, vertical, longitudinal section of a portion of the same, the section being taken substantially in line 3—3, Fig. 2; 70

Fig. 4 is a vertical transverse view of the machine, the section being taken in line 4—4, Fig. 1;

Fig. 5 is a transverse section and front elevation, taken in a line passing through 75 the needle opening in the bed-plate, of the pull-off mechanism, the same being shown in its position of maximum throw;

Fig. 6 is a similar view, showing said pull-off mechanism in its position of minimum throw; 80

Figs. 7 and 8 are views of goods containing a button-hole and illustrate the manner in which stitches are formed by the pull-off device, and 85

Fig. 9 is a detail illustrating in front elevation a throw-out device which will be hereinafter described.

Similar reference characters designate like parts in all the figures of the drawings. 90

My improved pull-off mechanism may be embodied in any suitable type of sewing machine, but is preferably employed in connection with a button-hole sewing machine, which may be a machine such as that illustrated in my prior application, Serial No. 779,984, filed July 19, 1913. The machine here illustrated is one substantially identical with that of my aforesaid application, to which reference may be made for further 100 description of such parts as are shown herein but are not connected directly with the operation of the pull-off mechanism. The machine shown comprises, among other things, a bed-plate 10, which carries in this 105 case all of the operating parts. At the front end of said bed-plate is the needle-plate 11, having therein the usual needle opening 12 to receive the needle n.

The work is clamped as usual, in a suit- 110

able work-clamp, *w*, and this work-clamp is adapted to be shifted crosswise of the machine by suitable work-holder-shifting mechanism. It will also have the usual longitudinal step-by-step movements to make successive stitches in each row of button-hole stitching. All of these parts are or may be the same as those described in my aforesaid application.

- 10 The pull-off mechanism is one suitable for the purpose of drawing off an additional amount of thread wherever this is necessary or desirable, and it is preferably one in which the additional thread is drawn off 75
- 15 from the bobbin for the purpose of making button-holes with a properly positioned "purl". The movement of the pull-off device may be any suitable for the purpose of 80 accomplishing the desired result, provided 85
- 20 it is a variable one in the general direction of the pull-off path, the extent of such movement depending upon the amount of additional thread to be pulled off, if any. Here a pull-off device is employed, such as indicated at *p*.

This pull-off device *p* is of the same general type as that disclosed in the aforesaid Patent #805,870, granted November 28, 1905, that is to say, it is a pull-off operative 90

30 at every alternate stitch for the purpose of locating the "purl" at the inner edge of the button-hole, to do which it is necessary that the pull-off action take place on every outer-edge stitch of the two rows of button-hole 95

35 stitches at the opposite edges of the button-holes. In order to do this it is necessary to reverse the timing of the pull-off upon the shifting of the work-clamp for presenting the opposite edge of the button-hole to 100

40 the stitching mechanism. This reversal of the timing relation of phase of the pull-off is controlled, as before indicated, from the shifting mechanism which includes the main cross-slide 62.

45 The connections from this main cross-slide 62 to the lower-thread pull-off may be any suitable for the purpose. Here a depending bracket, 126, is secured to the under side of the bed-plate of the machine and has, at its 105

50 upper and lower ends respectively, vertical bearings for a rock-shaft, 127, carrying at its upper and lower ends respectively two rock-arms, 128 and 129, the upper of which is a short forked rocker and co-operates with 110

55 a pin, 130, secured to the under side of the shifting-bar 99, which is pivotally connected to an extension 110 of the main cross-slide 62, so that said shifting-bar and cross-slide will move together. At its free end the lower 115

60 rock-arm 129 is pivotally connected to the rear end of a rod, 131, the forward end of which is reduced and has a stop, such as the adjustable nut, 132, between which and the shoulder at the opposite end of the reduced 120

65 portion of the rod two springs, 133 and 134,

are intended to work. These springs are separated from each other by the opposite sides of the bored ear (through which the reduced portion of the rod 131 passes) of a rocker, 135, extending from and forming in substance a part of a large rock-arm, 136, secured to a short lower rock-shaft, 137, at the front end of the machine which rock-shaft is journaled in depending portions, 138 and 139, of the main frame. This rock-shaft, in addition to having the usual turning movement, is also mounted to reciprocate longitudinally of its axis and with it the connected rock-arm 136, which has a wide forked end adapted to span a rearwardly projecting hub, 140, extending from a large spur-gear, 141, mounted to turn on a stud, 142, secured to the bracket 139. This hub 140 is extended sufficiently far to provide room for a central neutral space or rounded hub portion with which the forked rock-arm 136 may co-operate, and also for a pair of substantially triangular cams disposed oppositely to each other and located at opposite sides of such neutral or circular portion of the hub. These cams are indicated at 143 and 144 respectively. 90

The construction of the parts so far described is such that in the making of a button-hole during the stitching of the first row of regular button-hole stitches the forked rock-arm 136 will co-operate with the rear triangular cam 144 and will remain upon it and be rocked back and forth by it intermittently once for each two rotations of the 100 looper-shaft 145. The rocking motion of the arm 136 will, of course, be transmitted to its rock-shaft 137 (then in its extreme rearward position) and by it to a forward rock-arm, 146, slotted at its free end to receive the rear end of a pin, 147, carried by a rock-link, 148, pivoted at its left-hand end to the lower end of the pivoted lower-thread pull-off *p*, the pivot of which is indicated at 110

151. At its right-hand end the link 148 has pivoted thereto a block, 148', movable in an arc-shaped slot 153 in a rock-arm, 152, secured to a long rock-shaft, 74, operated by an eccentric-rod, 23, from the main upper drive-shaft 21. By these connections the pull-off 115

will be operated in a manner controlled by the conjoint action of the two rock-shafts 137 and 74. Thus, when the block 148' is 120

near the lower end of the slot 153 in the work-arm 152 as shown in Fig. 5, it has its maximum movement as imparted thereto by the rock-arm 152, because it is then at its maximum distance from the axis of the shaft 74, and the connected pull-off device *p* 125

has a correspondingly great arc of oscillation which is imparted to the bobbin-case to cause a corresponding movement thereof and the drawing off of the maximum amount of additional thread from the bobbin. When, however, the block 148' is near the upper 130

end of the slot 153, as in the position shown in Fig. 6, it has its minimum or practically its minimum stroke, owing to the fact that it is at or substantially at its least distance from the axis of said shaft 74 and the stroke of the connected pull-off p is correspondingly short, it being in the illustration in Fig. 6 only sufficient to draw off a slight additional amount of thread from the bobbin. 5 At each stroke of the needle the block 148' will be shifted to one or the other of the positions shown in Figs. 5 and 6, it being shifted first to one and then to the other alternately in order that a considerable additional amount of thread may be supplied 10 at each alternate stitch to provide for the proper formation and location of the purl. 15 Whether the forked rock-arm 136 is swung back and forth in one path by the cam 144 for one row of button-hole stitches, or is swung back and forth in another path by the cam 143 for the opposite row of stitches depends upon the longitudinal position of the rock-arm 137, which in turn is dependent 20 upon the action of the rod 131 and the movement of the shifting-bar 99. The movements of this shifting-bar are preferably derived, as in my aforesaid application, from a cam carried by and encircling the axis 25 of a rotary member, 18, which constitutes in this case, as in the former, the main rotary controller for governing most of the movements of the various mechanisms of the sewing machine. The cam carried by 30 the rotary controller 18 is shown as a cam-groove having four main parts, indicated at 106, 107, 108 and 109, and these sections of the cam correspond respectively to the first row of short or regular stitches, to the 35 long or barring stitches at the end of the first row of regular stitches to the second row of short regular stitches and to the second row of long or barring stitches which are made to complete a button-hole. 40 Which set of stitches will be made at a given time will depend upon the position to which the shifting-bar 99 is moved by one or another of said four sections of the cam-groove, which in turn will depend upon which section 45 of said cam-groove is in engagement with the pin 104 secured to said shifting-bar and operatively connecting it with said cam. As said shifting-bar is rocked in one direction or the other by the walls of this 50 cam-groove the connections to the forked rock-arm 136 will be correspondingly actuated as before described. 55

The rock-arm 136 remains upon the cam 144 throughout the making of the first row 60 of regular button-hole stitches; and throughout the making of the first set of long or barring stitches at the rear end of the button-hole, said rock-arm 137, which is gradually shifted forward during the making of 65 said barring stitches, leaves the cam 144 and

travels upon the neutral or circular portion 140 of the hub, against which it is moved by the action of a spring 155 which normally turns the rock-shaft 137 to the left. Immediately thereafter, on the shifting of the 70 main cross-slide 62 into position for forming the second row of button-hole stitches, the mechanism controlling the longitudinal movement of the rock-shaft 137 is operated and shifts the rock-arm 136 quickly on to 75 the opposite triangular cam 143, the rock-shaft 137 with its arm 146 moving forward at this time. This action results in reversing the timing relation of the pull-off action for the lower thread to assure the formation of the purl at the inner edge of the succeeding row of short button-hole stitches. In this shifted position of the rock-arm 136 the spring 134 is put under tension and serves to hold the parts just described in 80 their forward position, while when in the opposite position the tension on the spring 134 is released and tension put upon the spring 133 to hold said parts in their rearward position, *i. e.* tension is put upon one 85 spring and released from the other in one condition of the parts and is put upon the second spring and released from the first in the opposite condition of the parts. 90

The spur-gear 141 which controls the movements of the triangular cams and forked rock-arm just described is driven, in this case, from the looper-shaft 145 by a spur-pinion, 156, in constant mesh therewith. Said looper-shaft in turn is driven from the main upper 95 drive-shaft through sprocket-wheel and chain connections, indicated at 157, 158, and 159. The lower sprocket-wheel 159 is carried near the extreme rear end of a short shaft, 160, journaled in the lower rear main 100 bearing, 161, and carrying at its forward end a slotted rock-arm, 162, in the slot of which works a crank-pin 163, carried by a crank-arm, 164, secured to said looper-shaft, which shaft has its axis at some distance 105 below the main lower drive-shaft 160. This construction of course is for the purpose of obtaining the desired variable rotary movement of the looper-shaft and hence of the looper itself, as will be obvious. 110

An important feature of the invention is that the necessary additional amount of bobbin-thread is not only drawn off positively by the action of the pull-off device p but is drawn off by the positive turning of 115 the bobbin-holder by said pull-off. This bobbin-holder may be of any suitable construction for the purpose and is designated generally by 225. It is adapted to carry the bobbin and its thread in a well-known 120 manner, and has on the outside thereof a projecting element, such as 226, disposed in the path of the pull-off p and preferably between the two ends 227 and 228, of the 125 forked arm here illustrated as the specific 130

type of pull-off device used. It will be clear by reference to Figs. 5 and 6, that the actuating elements 227 and 228 of the pull-off device will positively turn the actuated element 226 of the bobbin-holder in the one direction or the other as the pull-off *p* swings back and forth, and it will also be clear that the extent of the turning movement of the bobbin-holder will be dependent upon that of said pull-off.

In Figs. 7 and 8 I have illustrated how the pull-off device acts upon the bobbin-thread 2 to draw off a sufficient quantity of thread, which may be much or little, to locate the purl in any one of various desired positions, away from the edge of the button-hole, as shown at 5, in Fig. 8, or at the edge of said button-hole, as shown at 6 in Fig. 7. Fig. 8 illustrates how the same quantity of thread is drawn off from the bobbin at each stitch and how the under thread is drawn by the needle-thread above the goods at the inner edge of the button-hole, as shown at 3, and how at the next stitch at the outer edge of the row said under thread is again drawn above the goods, as shown at 4, in said figure; while Fig. 7 illustrates the operation that takes place when the pull-off acts upon the bobbin-thread only at each alternate stitch when a sufficient quantity of additional thread is drawn from the bobbin, as shown at 7, to permit the thread pulled off to be drawn over to the inner edge of the button-hole and hence form the purl at said inner edge.

It will of course be evident that in this machine either a whip stitch or a purl stitch may be made. In making the plain or whip stitch the pull-off device for the lower thread is rendered ineffective in some suitable manner, as for example, by dropping a throw-out device in the form of a latch, 221, into a notch, 221', in the controlling rock-shaft 137 for the lower thread, which action results in locking said rock-shaft against longitudinal movement with the rock-arm on the central or neutral portion of the controlling device, that is, on the neutral portion between the cams 143 and 144, in which position said rock-arm 136 is ineffective to swing the block 148', the movement of which controls the amount of lower-thread pulled off from the bobbin.

What I claim is:

1. In a sewing machine, the combination with stitch-forming mechanism, of a bobbin-holder, a bobbin-thread pull-off coöperative with said bobbin-holder to turn the same and having a variable action in the general direction of the pull-off path, and means for operating said pull-off in said direction to act upon the bobbin-thread in a different manner for different stitches.

2. In a sewing machine, the combination with stitch-forming mechanism, of a bobbin-

holder, a bobbin-thread pull-off coöperative with said bobbin-holder to turn the same and having a variable action in the general direction of the pull-off path, and means for operating said pull-off in said direction to act upon the bobbin-thread at each alternate stitch.

3. In a sewing machine, the combination with stitch-forming mechanism, of a bobbin-holder, a bobbin-thread pull-off coöperative with said bobbin-holder to turn the same and being constantly maintained in its pull-off path, and means for operating said pull-off to act upon the bobbin-thread during the formation of certain predetermined stitches and to maintain said pull-off in inoperative relation with said bobbin-thread during the formation of certain other predetermined stitches.

4. In a sewing machine, the combination with work-holder-shifting mechanism, of a bobbin-holder, a thread-pull-off coöperative with said bobbin-holder to turn the same and having a variable action in the general direction of the pull-off path, and means controlled by said work-holder-shifting mechanism for operating said pull-off in said direction to act upon the thread in a different manner for different stitches.

5. In a sewing machine, the combination with stitch-forming mechanism, of a bobbin-holder, and a bobbin-thread pull-off coöperative with said bobbin-holder to turn the same, automatic means for varying the range of throw of said pull-off, and means for actuating said pull-off the determined distance in its pull-off path.

6. In a sewing machine, the combination with stitch-forming mechanism, of a bobbin-holder, and a bobbin-thread pull-off comprising an actuated element carried by the bobbin-holder and an automatic actuating element supported independently of the bobbin-holder and coöperative with said actuated element to turn said bobbin-holder different distances at different stitches.

7. In a sewing machine, the combination with stitch-forming mechanism, of a bobbin-holder having an actuated member, a pivoted bobbin-thread pull-off supported independently of the bobbin-holder and coöperative with said actuated member to turn said bobbin-holder, and means for operating said pull-off in determined timing different distances at different stitches.

8. In a sewing machine, the combination with stitch-forming mechanism, of a bobbin-holder having an actuated member, a pivoted forked bobbin-thread pull-off supported independently of the bobbin-holder and coöperative with said actuated member to turn said bobbin-holder positively in both directions, and means for operating said pull-off different distances at different stitches.

9. In a sewing machine, the combination

with stitch forming mechanism, of a bobbin-holder, and a bobbin-thread pull-off comprising an actuated element carried by the bobbin-holder and an automatic actuating element supported independently of the bobbin-holder and coöoperative with said actuated element to turn said bobbin-holder and having a variable throw.

10. In a sewing machine, the combination with stitch-forming mechanism, of a pivoted thread-pull-off, an actuating rocker for imparting a swinging movement to said pull-off, an operative connection from the pull-off to said rocker, and means shifting said connection at its rocker-engaging end in a direction toward and from the rocker axis at alternate stitches.

11. In a sewing machine, the combination with stitch-forming mechanism, of a thread-pull-off, an actuating rocker, a block slidably mounted on said rocker, an operative connection from the pull-off to said block, and means shifting said block toward and from the rocker axis at predetermined stitches.

12. In a sewing machine, the combination with stitch-forming mechanism, of a thread pull-off, an actuating rocker having a fixed

throw, a block slidably mounted on said rocker, a link pivotally connecting the pull-off with said block, and means shifting said block toward and from the rocker axis at predetermined stitches.

13. In a sewing machine, the combination with stitch-forming mechanism, of a thread-pull-off, an actuating rocker, a block slidably mounted on said rocker, an operative connection from the pull-off to said block, and means shifting said block toward and from the rocker axis at alternate stitches.

14. In a sewing machine, the combination with stitch-forming mechanism, of a thread-pull-off, an actuating rocker having a fixed throw, a block slidably mounted on said rocker, a link pivotally connecting the pull-off with said block, and means shifting said block toward and from the rocker axis at alternate stitches.

Signed at Cleveland, in the county of Cuyahoga, and State of Ohio, this 8th day of November A. D. 1913.

GEORGE W. NELSON.
